REFRIGERATION

Deane E. Perham and Ross A. Whitney, Chicago,
Ill.; said Perham assignor to said Whitney

Application March 13, 1939, Serial No. 261,562

6 Claims. (Cl. 62—31)

This invention relates to refrigeration and has for its principal object to enable foodstuffs and the like to be preserved under conditions which will materially mitigate the drying out thereof even if exposed in open dishes and to also afford a relatively low temperature to enable freezing of foodstuffs, such as ice cream, and to enable the preservation of foodstuffs requiring relatively low temperatures for this purpose.

10 While water ice has been used as a refrigerating medium for an appreciable time, it is only recently that resort has been had to arrangements which enabled water ice to be used in circumstances that would permit substantially uniform temperatures to be maintained in the compartments refrigerated by the use of such ice. Such arrangements entailed what is known as under ice circulation and in order that sufficiently low temperatures could be realized where 20 the circulation of air was confined to but a single face of a block of water ice or the like resort has been had to an arrangement which would increase the rate of heat transfer between air flowing from the space to be refrigerated and the block of ice. One such arrangement for enabling this to be accomplished is disclosed in the patent to Ophuls and Nuss, No. 1,864,212, patented June 21, 1932.

In the arrangement shown in the aforesaid patent a rack is provided which consists of a plurality of spaced apart substantially U-shaped metallic fins which are arranged to have the bights thereof extended upwardly so that when a block of water ice was rested thereon heat picked up by the fins would cause these fins to sink into the ice and thereby define fins of ice intermediate the metallic fins. Such fins of ice in cooperation with the metallic fins afford an area over which air from the space to be refrigerated can be passed that will insure that sufficient heat will 30 be picked up from the air to establish a refrigerating temperature in an enclosed area to which the air flows after having contacted the metallic and ice fins.

40 In an arrangement such as that disclosed in the aforesaid patent a drip pan has been arranged in spaced relation with the metallic and ice fins and air from the space to be refrigerated flowed over one end of the drip pan past the metallic and ice fins and out over the other end 45 of the drip pan into the space to be refrigerated. As the air flows over the ice fins in such an arrangement it contacts the wet surfaces of the ice and in addition flows through water dripping 50 from the melting ice to the drip pan therebelow, and this enables the humidity of the air to be maintained so that as the air flows over food in the compartment being refrigerated thereby, and even when it is exposed in open dishes, objectionable drying out of the food does not result.

5 However, in an arrangement such as the foregoing where the refrigerating medium was water ice it was not possible to obtain temperatures below 32° F.—the temperature of the refrigerating medium, water ice. However, particularly where refrigerators of this type have been employed for domestic purposes it has often been desirable to have temperatures lower than 32° F. in order to enable frozen desserts and the like to be expeditiously produced, and likewise to enable effective preservation of frozen foods and, of course, there are many other instances in which temperatures well below 32° F. are desirable. Such temperatures can be realized by the use of mechanical refrigerating equipment, 10 but where such equipment has been used to also refrigerate a space in which food products were to be preserved it has not always been possible to maintain such humidity in the air that the drying out of foodstuffs and the like exposed to 15 air refrigerated by contact with the cooling unit of a mechanical refrigerating system will be avoided.

20 It will be seen from the foregoing that there are advantages in employing water ice as a refrigerating medium and that there are also advantages in utilizing mechanical refrigerating equipment, and therefore an important object of this invention is to enable the advantages of both 25 types of refrigeration to be utilized in a single 30 apparatus.

35 In those instances where water ice is used as a refrigerating medium and air from the space to be refrigerated is caused to flow over but a single face of a block of such ice, as in the arrangement disclosed in the aforesaid Ophuls and Nuss patent, it has been customary to confine the block of ice in a compartment separate and apart from the compartment through which the air to be refrigerated is to flow. It has been observed 40 by reason of the inevitable heat leakages into the compartment in which a refrigerating medium, such as water ice, is to be confined that there has been an undesirable melting of the ice or other refrigerating medium, and hence another 45 important object of this invention is to absorb heat leaking into a compartment in which a block of ice or other refrigerating medium is stored in such a way as to prevent undesired and objectionable melting of such refrigerating medium, and an object ancillary to the foregoing is to provide an evaporator of a mechanical refrigerating system in a compartment in which a block of water ice or the like is adapted to be 50 stored so that heat leakages into the compartment can be absorbed by a refrigerating medium flowing through such evaporator.

55 Other and further objects of the present invention will be apparent from the following description and claims and are illustrated in the 60

accompanying drawings which, by way of illustration, show a preferred embodiment and the principle thereof and what we now consider to be the best mode in which we have contemplated applying that principle. Other embodiments of the invention embodying the same or equivalent principle may be used and structural changes may be made as desired by those skilled in the art without departing from the present invention and the purview of the appended claims.

In the drawings:

Fig. 1 is a front elevation of a refrigerator embodying our novel invention and wherein the doors of the refrigerator are shown open;

Fig. 2 is a vertical transverse sectional view through the refrigerator shown in Fig. 1;

Fig. 3 is a vertical longitudinal sectional view taken substantially on the line 3—3 on Fig. 2; and

Fig. 4 is a partially diagrammatic view of the mechanical refrigerating system incorporated in the refrigerator shown in Figs. 1, 2 and 3.

In the selected embodiment of our invention illustrated in the accompanying drawings, a refrigerator, generally indicated by 10, is shown as embodying an ice compartment 11 positioned above a food storage compartment 12, such compartments being defined by a lining 13 arranged in an outer casing 14, intermediate which lining 30 and casing suitable insulation 15 is provided. It will be understood that the particular construction and arrangement of the refrigerator and compartments as 11 and 12 therein forms no part of our invention inasmuch as any arrangement 35 which will enable a block of ice as 16 or other equivalent refrigerating medium to be utilized for the purpose of establishing a refrigerating temperature in a storage compartment as 12 will be sufficient for the purposes of this invention.

However, in the present instance a rack, generally indicated by 17 is provided intermediate the ice compartment 11 and the food compartment 12, this rack being supported by suitable ledges provided in the refrigerator construction 45 and comprising a plurality of spaced apart, substantially U-shaped metallic fins 18. As best shown in Fig. 1, the fins 18 have the bights thereof extended upwardly so that the block of ice 16 may be rested on these bights.

A drip pan 19 or an equivalent arrangement is supported below the rack 17 and, in cooperation with the rack and block of ice, defines a cooling and air conditioning chamber 20. It will be noted that the front and rear ends of the drip pan 19 are respectively spaced from the front and rear walls of the refrigerator and that this pan is arranged at the upper end of the food or storage compartment 12. Hence, air may flow from this compartment over the front end of the pan 60 19 and through the chamber 20 and out over the rear end of the pan 19 back into the food compartment 12. As the air flows through the compartment 20 it is cooled inasmuch as heat is picked up therefrom by the metallic fins 17 which thereupon sink into the ice to form fins of ice 65 therebetween, as best shown in Fig. 1, and these fins of ice cooperate with the metallic fins in reducing the temperature of air flowing through the compartment 20 so as to enable a refrigerating temperature to be set up in the compartment 12. Moisture will, of course, be present on the surfaces of the ice fins between the metallic fins 18, and furthermore as heat is transferred to the ice block 16 meltage thereof will occur, 70 75 wherefore water will drip across the chamber 20

into the drip pan 19, and such water will be discharged from the refrigerator through the usual drain pipe arrangement 21. By reason of the contact of air flowing through the chamber 20 with the moisture on the surfaces of the aforesaid ice fins and the water dripping across the chamber 20, the humidity of the air will be maintained sufficiently high to avoid objectionable drying out of foodstuffs exposed in open dishes stored in the compartment 12.

It has been explained that it is frequently desirable, particularly in domestic use of refrigerators, to have available a temperature lower than the 32° F. temperature of water ice and that this could be accomplished by using mechanical refrigeration. In the present instance this is realized by providing a compartment 22 at one corner of the compartment 12, this compartment 22 being defined in the present instance by an insulated wall 23 which cooperates with the bottom, rear and one side wall of the compartment 12 in order to define the compartment 22. Preferably a door 24 is provided at the front of the compartment 22 so that this compartment can be maintained isolated from the compartment 12, the door 22 being arranged so as not to interfere with the closing of the door 25 included in the refrigerator for closing the opening in the front wall of the refrigerator through which access is had to the compartment 12, and in the present instance also to the compartment 22, the door 24 being opened when access to this latter compartment is desired.

In the present instance an evaporator 26 is supported in the compartment 22 and this evaporator is shown as having drawers 27 associated therewith. It will, of course, be understood that a single drawer could be substituted for the two drawers 27 that are shown or other arrangement could be provided for utilizing the temperatures 40 made available by the evaporator 26 within the compartment 22, the drawers 27 and the particular manner in which the evaporator 26 is mounted in the compartment 22 merely being illustrative of a way in which the low temperature 45 in the compartment 22 may be afforded and utilized.

It has been explained that by reason of heat leakages through the walls of the compartment 11 and for other reasons there may be undesirable 50 and objectionable melting of a block of ice as 16 stored within such compartment, and it has also been explained that it is among the objects of this invention to prevent such undesirable and objectionable melting of the ice cake by providing an evaporator or the like in a compartment as 11 and to absorb heat leaking into the compartment by the refrigerating medium flowing through such evaporator. Thus in the present instance an evaporator 28 of the plate type 60 is supported by brackets 29 in the upper part of the compartment 11 and preferably the evaporator 28 is supported out of alignment with the opening 30, closed by the door 31, into the compartment 11 and through which a block of ice 65 as 16 is introduced into the compartment to either rest on the upper surface of a previously installed block of ice or to rest directly on the fins 18. It will be understood that in an arrangement where a rack as 17 is employed the ice melts downwardly and thereby affords a flat upper surface onto which another block of ice may be expeditiously slid when the first block of ice is substantially exhausted. This is a particularly advantageous arrangement for it not 70 75

- only insures that an ample supply of ice may be maintained in the refrigerator but it enables a substantially uniform temperature to be maintained in the compartment 12 irrespective of the size of the ice cake. By arranging the evaporator 28 out of alignment with the opening 30 the likelihood of damage to the evaporator when a block of ice is installed in the compartment 11 is avoided.
- 10 In the present instance the lower wall of the compartment 12 is arranged well above the bottom of the refrigerator 10 so that a compartment is provided at the bottom of the refrigerator. Furthermore, in the present instance a partition 15 32 is provided in this compartment at the bottom of the refrigerator to divide it into a storage compartment 33 in which utensils or the like may be stored and a compartment 34 in which in the present instance a compressor 35 and a condenser 36 of a mechanical refrigerating system are mounted, the compressor 35 in the present instance being driven by an electric motor 31, also mounted in the compartment 34, through a belt 38.
- 20 25 We have found that it is advantageous to maintain a relatively low temperature in an evaporator such as the evaporator 26 while it is not essential that so low a temperature be maintained in the evaporator located in the position of the evaporator 28, in the present instance. In view of this, liquid refrigerant from the condenser 36 is directed through a pipe 39 to a heat exchanger 40 and thence through a pipe 41 to an expansion valve 42 or other pressure reducing means, the expansion valve 42 in the present instance being mounted in the compartment 11. Liquid refrigerant passing through the expansion valve 42 flows through a pipe 43 to the evaporator 26 and thence through a pipe 44 to the evaporator 28 and from the evaporator 28 the refrigerant flows through a pipe 45 which passes through the heat exchanger 40 and returns to the compressor 35, refrigerant compressed in the compressor 35 flowing through the pipe 46 to the condenser 36.
- 40 45 Thus liquid refrigerant under relatively high pressure from the condenser 36 first flows through pipe 39 to the heat exchanger 40 where its temperature is reduced by the refrigerant returning to the compressor 35 through the pipe 45. Liquid refrigerant passed through the expansion valve 42 or other pressure reducing means is at a pressure lower than the pressure thereof in the pipe 41 and as such a refrigerant flows into the evaporator 26 it is at least partially evaporated therein to thereby establish a relatively low temperature in the compartment 22. After flowing from the evaporator 26 the refrigerant is admitted into the evaporator 28 where it serves the purpose of absorbing heat that leaks into the compartment 11 and where it also serves to maintain a block of water ice as 16 or the like at a temperature lower than its melting point and thereby undesirable and objectionable meltage of a block of ice as 16 is prevented. Refrigerant passing from the evaporator 28, as stated heretofore, somewhat reduces the temperature of refrigerant flowing to the expansion valve 42 as it flows through the heat exchanger 40 and returns to the compressor 35 to have the pressure thereof increased to facilitate liquefaction thereof in the condenser 36.
- 50 55 It will be understood that regardless of what construction is employed to enable a refrigerating medium, such as water ice, to be used for the purpose of establishing a refrigerating tempera-
- ture in a storage compartment as 12, it will be desirable that air circulated through such a storage compartment be prevented from contact with the evaporator or evaporators of the mechanical refrigerating system employed as above. This is accomplished by an arrangement such as that shown in the accompanying drawings by confining the circulation of air to the underside of the ice for so to do prevents the air from coming in contact with an evaporator, such as the evaporator 28 in the present instance, and this is also accomplished by isolating an evaporator such as the evaporator 26 from the storage compartment 12.
- 60 65 It will be manifest from the foregoing description that we have realized the above set forth objects of this invention inasmuch as by the utilization of an arrangement such as that hereinabove described it is possible to establish a refrigerating temperature in a storage compartment as 12 and to effect this by the use of water ice as a refrigerating medium which, as explained hereinabove, has the advantage of enabling food to be stored in the compartment as 12 in such a way as to be exposed to the air circulated in the refrigerating compartment without objectionable drying out of the food. At the same time we have made available a temperature such as can be utilized for the preservation of frozen foods or for the production of frozen desserts and the like, 30 and this latter has been accomplished by utilizing a mechanical refrigerating system and arranging an evaporator included in such system in such a way that the temperature established by the evaporation of a refrigerating medium in such evaporator may be utilized for the aforesaid and like purposes. Moreover, we have prevented undesirable and objectionable meltage of the water ice in the compartment in which it is stored in a refrigerator or the like.
- 70 75 It is to be understood that while we have shown and described a preferred embodiment of our invention this is capable of variation and modification and we therefore do not wish to be limited to the precise details set forth but desire to avail ourselves of such changes and alterations as fall within the ambit of the following claims.
- We claim:
1. In a refrigerator including a storage compartment and a refrigerating medium compartment, means for directing a flow of air from and to the storage compartment past a refrigerating medium housed in the refrigerating medium compartment to thereby cool the air and enable a refrigerating temperature to be established in the storage compartment, a mechanical refrigerating system in said refrigerator including at least two evaporators, means providing a compartment in the refrigerator in which one of such evaporators may be arranged to enable a relatively low temperature to be established in such compartment, and means supporting another of such evaporators in the refrigerating medium compartment out of the primary path of air flow past the refrigerating medium to thereby enable such a temperature to be established in such compartment that undesirable and objectionable meltage of the refrigerating medium stored therein may be prevented.
  2. In a refrigerator including a storage compartment and a refrigerating medium compartment, means for directing a flow of air from and to the storage compartment past a refrigerating medium housed in the refrigerating medium compartment to thereby cool the air and enable a

- refrigerating temperature to be established in the storage compartment, a mechanical refrigerating system in said refrigerator including at least two evaporators, means providing an auxiliary compartment in the refrigerator in which one of such evaporators may be arranged, means supporting another of such evaporators in the refrigerating medium compartment out of the primary path of air flow past the refrigerating medium, and means in said system for regulating the operation of said evaporators, said evaporators and said regulating means being so arranged in said system that a relatively low temperature is established by the evaporator in said auxiliary compartment and a temperature higher than such relatively low temperature is established by the evaporator in such refrigerating medium compartment. 5
3. In a refrigerator including a storage compartment and a refrigerating medium compartment, means for directing a flow of air from and to the storage compartment past a refrigerating medium housed in the refrigerating medium compartment to thereby cool the air and enable a refrigerating temperature to be established in the storage compartment, means providing an auxiliary compartment in, but out of communication with, the storage compartment, means providing a still further compartment in said refrigerator, a mechanical refrigerating system including means for condensing a refrigerating medium and two evaporators, the condensing means of said system being arranged in said further compartment, one of said evaporators being mounted in said auxiliary compartment and another of said evaporators being mounted in the refrigerating medium compartment out of the primary path of air flow past the refrigerating medium, means interconnecting said condensing means and said evaporators and through which a refrigerating medium may flow, and means in the interconnecting means for regulating the admission of the refrigerating medium into said evaporators, said interconnecting means and the regulating means being so arranged that a relatively low temperature is established by the evaporator in said auxiliary compartment and a temperature higher than such relatively low temperature is established by the evaporator in said refrigerating medium compartment. 10
4. In a refrigerator including a food compartment and an ice compartment, a rack supported intermediate said compartments and having a plurality of spaced apart heat conductive fins thereon adapted to sink into a cake of ice engaged therewith to form fins of ice on said cake intermediate the heat conductive fins, a drip pan disposed below said rack and cooperating with said rack and an ice cake thereon to provide an air cooling and conditioning chamber through which air from said food compartment may flow to be cooled and conditioned to be returned to said food compartment to establish a refrigerating and food preserving condition therein, a refrigerating system in said refrigerator including at least two evaporators, means providing a compartment in the refrigerator in which one of said evaporators may be arranged to enable a relatively low temperature to be established in such compartment, and means supporting another of such evaporators in the ice compartment to thereby enable such a temperature to be established in such compartment that undesirable and objectionable meltage of a cake of ice stored therein may be prevented. 15
5. In a refrigerator including a food compartment and an ice compartment, a rack supported intermediate said compartments and having a plurality of spaced apart heat conductive fins thereon adapted to sink into a cake of ice engaged therewith to form fins of ice on said cake intermediate the heat conductive fins, a drip pan disposed below said rack and cooperating with said rack and an ice cake thereon to provide an air cooling and conditioning chamber through which air from said food compartment may flow to be cooled and conditioned to be returned to said food compartment to establish a refrigerating and food preserving condition therein, a mechanical refrigerating system in said refrigerator including at least two evaporators, means providing an auxiliary compartment in which one of said evaporators may be arranged, means supporting another of such evaporators in the ice compartment, and means in said system for regulating the operation of said evaporators, said evaporators and said regulating means being so arranged in said system that a relatively low temperature is established by the evaporator in said auxiliary compartment and a temperature higher than said relatively low temperature is established by the evaporator in said ice compartment. 20
6. In a refrigerator including a food compartment and an ice compartment, a rack supported intermediate said compartments and having a plurality of spaced apart heat conductive fins thereon adapted to sink into a cake of ice engaged therewith to form fins of ice on said cake intermediate the heat conductive fins, a drip pan disposed below said rack and cooperating with said rack and an ice cake thereon to provide an air cooling and conditioning chamber through which air from said food compartment may flow to be cooled and conditioned to be returned to said food compartment to establish a refrigerating and food preserving condition therein, means providing an auxiliary compartment in, but out of communication with, the food compartment, means providing a storage compartment in said refrigerator, a mechanical refrigerating system including means for condensing a refrigerating medium and a pair of evaporators, the condensing means of said system being arranged in said storage compartment, one of said evaporators being mounted in said auxiliary compartment and the other of said evaporators being mounted in the ice compartment in a position to avoid engagement therewith of a cake of ice introduced into said compartment, means interconnecting said condensing means and said evaporators and through which a refrigerating medium may flow, and means in the interconnecting means for regulating the admission of the refrigerating medium into said evaporators, said interconnecting means and said regulating means being so arranged that a relatively low temperature is established by the evaporator in said auxiliary compartment and a temperature higher than such relatively low temperature is established by the evaporator in said ice compartment. 25
